Primary Examiner—Lucy Lieberman**[57]****CLAIM**

The ornamental design for a plastic container, as shown and described.

DESCRIPTION

FIG. 1 is a side elevational view of a plastic container showing my new design;
 FIG. 2 is an end elevational view taken from the right in FIG. 1;
 FIG. 3 is a bottom plan view;
 FIG. 4 is an end elevational view taken from the left in FIG. 1;
 FIG. 5 is a top plan view;
 FIG. 6 is a perspective view;
 FIG. 7 is a fragmentary sectional view taken along the line 7—7 in FIG. 1;
 FIG. 8 is a side elevational view of another embodiment of the design;
 FIG. 9 is a bottom plan view;
 FIG. 10 is an end view taken from the right in FIG. 8;
 FIG. 11 is an end view taken from the left in FIG. 8;
 FIG. 12 is a perspective view; and,
 FIG. 13 is a top plan view.
